COATING METHOD AND APPARATUS

William F. Grupe, Lyndhurst, N. J., assignor to
Interchemical Corporation, New York, N. Y., a
corporation of Ohio

Application April 15, 1941, Serial No. 388,573

6 Claims. (CL 117—7)

This invention relates to the art of coating metal and aims to provide an improved method and apparatus by means of which metal, in the form of a thin continuous strip, may be effectively covered, preferably on both sides thereof, with a thin and uniform coating of lacquer, varnish, or the like.

When thin gauge metal, such as is used in the manufacture of small food containers, is provided in strip form, it usually is not perfectly flat throughout its length and width. Some of the unevenness in the stock may be caused by improper camber in the rolling mills; or if a particular strip which is to be coated has been cut from one of greater width, the edge or edges which have been cut are usually wavy or scalloped due to too deep a set of the slitter knives, the pitch of the waves or scallops varying with the depth of set of the blade. Moreover, the cut edges are often blurred. When attempts are made to coat such strip metal with apparatus now available, it is usually not possible to overcome the unevenness or tendency to twist with the tensions that are applied in normal coating apparatus. This creates at least two important difficulties in the coating operation: first, it is not possible to obtain a uniform thickness of coat throughout the width of the strip; and second, the scalloped and burred edge actually cuts into the usual resilient surfaced coating rollers, particularly when a reverse roll coater is employed. While this latter trouble is primarily one which involves the coating apparatus, it will be understood that any appreciable cutting into the coating rollers will ultimately affect the coating operation. Furthermore, because of the relatively large diameters of the usual coating rollers, the coating tends to form streaks or ridges which are particularly pronounced when the coating material is pigmented. These and other difficulties have been of such a nature that there are not any available commercial machines or methods for properly coating thin strip metal, such as is used for manufacturing food containers and the like.

According to my invention, the strip metal to be coated and under suitable tension is covered on one side with an excess of the desired coating material and is then bent transversely at an angle of from about 3° to 30° by breaking the strip over a bar of very small diameter which is positioned along the line of the bend and is constructed and arranged so that the coating, throughout the entire width of the strip, is leveled to a uniform layer free of ridges and all excess coating is removed as the strip passes thereover. Where the

coating is applied to both sides of the metal web, two small diameter bars are employed and arranged so that the angle between the plane in which the strip is being fed and a plane passing through centers of the bars is between 3° and 30°. The coated strip is first broken over one bar which levels and regulates the thickness of the layer on one side, and is then bent back by breaking over the second bar which levels and regulates the thickness of the layer on the other side. By proceeding in this manner, both sides of a wavy strip of metal may be continuously coated throughout the width of the strip with a uniform and regulated layer of coating material free from all streaks, ridges or unevenness.

The above and other features and objects of the invention will become apparent on consideration of the following detailed description and the accompanying drawing, in which:

Fig. 1 is a diagrammatic elevational view of an apparatus for continuously coating strip metal in which the apparatus features of my invention have been embodied; and

Fig. 2 is a fragmentary perspective detail view, with certain dimensions exaggerated for the sake of clarity, of one form of bar for bending a strip and leveling and regulating the coating applied upon one side thereof.

Referring now to the drawing, it will be observed that a strip of thin gauge metal 5 is fed from a suitable supply reel or coil 6 upwardly over a feed or guide roll 7 into a cleaning chamber 8. This cleaning chamber 8 may be of any conventional construction and contains some material, such as trichlorethylene, for cleaning the strip 5 as it passes therethrough over a large guiding drum 10 and upwardly to a second guiding roller 11. From the roller 11, the strip passes downwardly and around a guide roller 12 to a pair of brake rollers 13 and 14. These rollers are of a rather large diameter and cause the strip to be flattened out somewhat in passing around them in the path shown in Fig. 1. The strip is then fed in a substantially horizontal path through a coating apparatus, which is designated as a whole by the reference numeral 15, where it is coated on both sides thereof with a layer of any desired coating material. Said strip is next passed through a heating chamber 16 for drying the applied coating, a cooling chamber 17 and into a pull and feed apparatus which includes rollers 18, 20, 21 and 22 that are driven and arranged to grip the metal sufficiently to feed or pull it through the entire apparatus. The web or strip 5 may be passed from the uppermost roller 22 to

a rewind reel 23, or it may be cut into sheets in any conventional manner, if desired.

In one form of coating apparatus that has been tried, the strip 5 extends in a horizontal path from the upper brake roller 14 to the lowermost roller 18 of the feed and pull apparatus and is substantially unsupported throughout this distance. The braking power of the rubber covered braking rollers 13 and 14 is used to provide a sufficient resistance for maintaining the supported strip taut and in a horizontal plane; and sufficient tension is provided to cause the strip to be in proper position for coating. However, due to the fact that the strip metal is usually not flat, because of conditions encountered in its manufacture, and has at least one sharp and scalloped edge, difficulties are encountered in the coating operation.

Where the strip metal is to be used in the manufacture of containers, it is desirable to provide a thin coat of protective material that is entirely continuous, free of porosity, and of uniform protective value over the entire surface of the metal. Such coated stock is then formed into cans or containers and during fabrication may be bent either in easy turns or sharply in crimping and closing the side seams for the containers; or it may be shaped and drawn, as in making the can ends when sharp draws are made which actually distort the metal. Some of the fabricating operations cause the strip to be bent 180°. Because of these strenuous fabricating operations, it is essential that the coating applied to the strip be uniform and of a minimum thickness so as to provide proper protection. If the coating is uneven or heavy, it will crack, or lose its bond at the sharp ends so as to expose the metal to corrosion. The thinner the coating is applied, the more economical is the operation and the easier it is to make the necessary bends during fabrication without undue stretching of the outer surface of the coating, thus avoiding any break in the coated surface.

At the present time, all metal coating is done with roller coaters in which the rollers are of rather large diameter ranging from 10 to 14 inches. These rollers usually have a resilient surface of some gelatine or rubber compound. Due to the rather large diameter of the rollers, there is a long surface contact between the roller and the metal surface, and the coating contacting the metal and the roller is gradually split as the roller revolves. For a roller 10 inches in diameter, this surface contact is always at least one inch in length. Depending upon the viscosity and the amount of coating material applied, it has a tendency to gather in streaks as it approaches the breaking point. This results in rather high ridges which run longitudinally of the strip and may be spaced at distances from $\frac{1}{2}$ of an inch in low viscosity material to $\frac{1}{4}$ or $\frac{3}{8}$ of an inch in the heavier and more viscous materials; these coating streaks or ridges not only destroy the protective value of the coating or final beauty or finish of the material, but obviously create an undesirable waste of coating material.

In accordance with my invention, strip steel that is not flat and may be twisted, scalloped or burred, is coated with a thin and uniform layer of the desired coating material by applying an excess of the coating to one or both sides thereof and then bending the strip transversely at an angle of from about 3° to 30° by breaking the strip over a bar of very small diameter which is positioned along the line of the bend and is con-

structed so that the coating, throughout the width of the strip, is leveled to a uniform layer free of ridges and all excess coating is removed. By maintaining the metal under suitable tension and bending at such angles, it is made entirely flat along the line of the bend; and by using a bar or roller of extremely small diameter, such as $\frac{1}{4}$ inch, the surface contact is reduced to a minimum and the coating streaks or ridges referred to above are entirely eliminated. I have found that with a $\frac{1}{4}$ inch bar the surface contact does not exceed $\frac{1}{8}$ inch, and in most cases the coating is split in a distance of $\frac{1}{8}$ of an inch beyond the line of contact. With such a short rapid break, there is no noticeable streak formation.

The coating apparatus 15 comprises an upper resilient surface coating roller 25 which receives coating material from a feed or distributing roller 26 and cooperating fountain roller 27, the latter of which is arranged to rotate in a bath 28 of the coating material. This upper surface coater is of conventional construction and the setting of the rollers 25, 26 and 27 is such that a layer of the coating material will be applied upon the upper surface of the strip 5 as it passes beneath and in contact with the coating roller 25. A supporting and guiding roller 30 is positioned on the lower side of the web or strip 5 between the coating roller 25 and a second coating roller 31 which is supplied with coating material in the desired excess quantities by means of a fountain roller 32 rotating in a bath 33 of the coating material. The strip 5 is shown as maintained in a substantially horizontal position in passing from the braking roller 14 through the parts of the coating apparatus thus far described and is thus coated on both sides thereof with a slight excess of the coating material. All of the parts of the coating apparatus are positioned as closely together as possible; and the intermediate supporting roller is of extreme importance in insuring a suitable flat contact with the coating rollers 25 and 31 and in avoiding such twisting of the strip as would render the apparatus inoperative.

Upon passing beyond the coating roller 31, the strip 5 is bent upwardly through an angle of from 3 to 30°, depending primarily upon the thickness or gauge of the particular strip of metal being coated, by breaking the strip 5 over a small diameter bar 34; for strip steel 0.010 inch thick an angle of 10° has been found particularly suitable. As shown in Fig. 2, the bar 34, which is about $\frac{1}{8}$ to $\frac{3}{8}$ of an inch in diameter, is wound with fine wire 35 so as to provide a series of uniform and regularly spaced grooves 36 throughout the length thereof. In passing a web over such a bar, it will act to regulate the thickness of the coating material due to the provision of the grooves 36; and the windings provide a spiral surface which, when rotated, create a feeding action that serves to carry any undesirable foreign matter over the edge of the strip where it may be caught in a suitable pan. However, when the wire 35 is omitted the bar still functions satisfactorily but provides an even thinner layer. As mentioned above, it is the small diameter and resulting short surface contact which I have found to be particularly important in eliminating the undesirable streaks and ridges in the applied coating.

In the present instance, the bar 34 is mounted in a suitable bearing 37 and provided at one end thereof with a driving gear or sprocket 38 which may be connected up to any convenient source of power so as to rotate the bar 34 continuously during the coating operation. The bar is rotated in

the direction of movement of the strip and preferably at a surface speed somewhat less than that of the strip so as to exert a slight scraping action, the relative speeds of the strip and bar thus acting additionally to control the weight of the coating applied. I have found that the rotating bar is suitably lubricated in its bearing by the excess coating material. By bending the strip 5 over the bar 34 under tension in the manner described, said bar will cause the strip to be straightened completely along the bar 34 and throughout the width of the strip which thus contacts the bar uniformly throughout its width and accurately regulates and levels the coating material that has been applied to the upper surface of the strip 5 by the coating roller 25. In any case, the tension provided by the feed and pull unit and the braking rollers should be sufficient to cause the strip to be properly bent along a straight line in passing over the bar 34. For strip steel of 0.010 inch thickness, this tension may be about 50 pounds per lineal inch of width of the strip.

Similarly, the coating material applied to the lower part of the strip is regulated and leveled into a uniform layer free of streaks or ridges by bending said strip back to a substantially horizontal plane, i. e., bending it through an angle of from 3 to 30°. This is accomplished by breaking the strip 5 over a small diameter bar 40 mounted for rotation in a suitable bearing 41. This second leveling bar performs the same action on the coating material applied to the lower side of the web and is substantially identical in construction and operation with the bar 34.

With both sides of the strip 5 thus coated with a very thin and uniform layer of coating material, said strip is thus passed through the heater 16 where the coating, due to its uniformity and regulated thickness, is quickly and effectively dried; and the strip may then be cooled and rewound as described above.

From the foregoing description, it will be understood that, by the present invention, I have provided an improved method and apparatus by means of which strip metal may be continuously coated on one or both sides with a thin and uniform layer of any desired coating material free from streaks or ridges and accurately regulated throughout the entire width of the strip. Various changes may be made in the construction and method described and certain features or steps thereof may be employed without others, without departing from my invention or sacrificing any of its advantages.

What I claim is:

1. A method of continuously coating a side of a traveling strip of metal with a thin and uniform layer of a coating material, which comprises maintaining said strip under tension; covering one side of said strip with an excess of the coating material; and bending said strip transversely through an angle of from 3° to 30° by breaking the strip and drawing it over a small diameter bar with the coated side in contact with said bar, the amount of tension and the angle of bend being sufficient to cause said strip to become entirely flat along the line of bend, so as to obtain complete contact between said strip and said bar throughout the width of said strip, but insufficient to cause a permanent deformation of said strip.

2. A method of continuously coating a side of a traveling strip of metal with a thin and uniform layer of a coating material, which comprises maintaining said strip under tension; covering

one side of said strip with an excess of the coating material; and bending said strip transversely through an angle of from 3° to 30° by breaking the strip and drawing it over a bar rotating in the direction of movement of the strip and having such a small diameter that said strip has no greater than $\frac{1}{8}$ inch lineal surface contact therewith, the amount of tension and the angle of bend being sufficient to cause said strip to become entirely flat along the line of bend, so as to obtain complete contact between said strip and said bar throughout the width of said strip, but insufficient to cause a permanent deformation of said strip.

3. A method of continuously coating both sides of a traveling strip of sheet metal with a thin and uniform layer of a coating material, which comprises maintaining said strip under tension; covering both sides of said strip with an excess of coating material; bending said strip transversely through an angle of from 3° to 30° by breaking the strip and drawing it over a small diameter bar with one surface thereof in contact with said bar; and bending said strip transversely through an angle of from 3° to 30° by breaking the strip and drawing it over a small diameter bar with the other surface in contact with said bar, the amount of tension and the angle of bend in each instance being sufficient to cause said strip to become entirely flat along the line of bend, so as to obtain complete contact between said strip and said bar throughout the width of said strip, but insufficient to cause a permanent deformation of said strip.

4. A method of continuously coating a side of a traveling strip of metal with a thin and uniform layer of a coating material, which comprises maintaining said strip under tension; covering one side of said strip with an excess of the coating material; and bending said strip transversely through a predetermined angle by breaking the strip and drawing it over a small diameter bar with the coated side in contact with said bar, the amount of tension and the angle of bend being sufficient to cause said strip to become entirely flat along the line of bend, so as to obtain complete contact between said strip and said bar throughout the width of said strip, but insufficient to cause a permanent deformation of said strip.

5. Apparatus for continuously coating both sides of a traveling strip of sheet metal with a thin and uniform layer of a coating material, which comprises means for maintaining said strip under tension in its traveling movement; means for covering one side of said strip with an excess of the coating material; means for covering the other side of said strip with an excess of the coating material; a first regulating and leveling bar of from $\frac{1}{16}$ to $\frac{1}{8}$ of an inch in diameter disposed in the path of said strip so that one side will contact therewith; a second regulating and leveling bar of from $\frac{1}{16}$ to $\frac{1}{8}$ of an inch in diameter arranged beyond said bar so that the other side of said strip will contact therewith, the arrangement of said bars being such that said strip will be bent through an angle of from 3° to 30° in passing over each of them; and means arranged between said covering means for supporting said strip in its traveling movement between them.

6. Apparatus for continuously coating both sides of a traveling strip of sheet metal with a thin and uniform layer of a coating material, which comprises means for maintaining said strip under tension in its traveling movement, said

tension being equivalent to a tension of 50 pounds per lineal inch of width for a metal strip 0.010 inch thick; means for covering one side of said strip with an excess of the coating material; means for covering the other side of said strip with an excess of the coating material; a first regulating and leveling bar of from $\frac{1}{16}$ to $\frac{1}{8}$ of an inch in diameter disposed in the path of said strip so that one side will contact therewith; a

second regulating and leveling bar of from $\frac{1}{16}$ to $\frac{1}{8}$ of an inch in diameter arranged beyond said bar so that the other side of said strip will contact therewith, the arrangement of said bars being such that said strip will be bent through an angle of from 3° to 30° in passing over each of them; and means for rotating each of said bars in the direction of movement of said strip.

WILLIAM F. GRUPE.
